His Attorney.

UNITED STATES PATENT OFFICE.

ARTHUR G. ZIMMERMAN, OF SCHENECTADY, NEW YORK, ASSIGNOR TO GENERAL ELECTRIC COMPANY, A CORPORATION OF NEW YORK.

SOUND-REPRODUCING DEVICE.

Application filed January 29, 1927. Serial No. 164,620.

My present invention relates to sound reproducing apparatus of the type commonly known as loud speakers, and more particularly to a form of vibrating conical paper or fibrous diaphragm adapted to be employed in connection with such apparatus.

In the operation of loud speakers employing thin paper conical diaphragms, considerable difficulty has been encountered owing to the tendency of such diaphragms to rattle at certain frequencies. This action is due to circumferential, parasitic vibrations which are set up in the body of the cone, causing the cone to depart from a circular cross section into a distorted irregular section the displacement of which introduces rattles at certain frequencies. Some of these vibrations result from the use of a relatively long drive rod between the vibrating armature of the actuating mechanism and the cone, while others occur under the piston action of the cone, at large amplitudes. Owing to mechanical limitations, it is difficult to make the drive rod short enough to eliminate the circumferential vibrations. I have found, however, that by the provision on the cone of a plurality of properly spaced, embossed rings of a certain radius that these vibrations in the diaphragm may be prevented and rattling substantially eliminated.

While it is not unusual to employ corrugations in connection with flat or substantially flat, metallic diaphragms, such corrugations have been employed to provide lateral stiffness in the diaphragm. In the present case the corrugations provide additional rigidity in the cone but at the same time substantially eliminate circumferential, parasitic vibrations.

The novel features which I believe to be characteristic of my invention are set forth with particularity in the appended claims. My invention itself will best be understood by reference to the following specification when considered in connection with the accompanying drawing in which Fig. 1 represents a perspective view of the diaphragm embodying the features of my invention, while Fig. 2 is a view partly in section and partly in elevation of a portion of the diaphragm and the actuating mechanism therefor.

Referring to the drawing, I have indicated at 1 a conical diaphragm having an angle

at its apex of about 105° and a base about 7 55 inches in diameter. The diaphragm consists of paper about 6 mils in thickness and is provided at its apex with an opening 2 which is adapted to be covered by a thin metal spider 3. The latter is usually cemented to 60 the diaphragm and provides means whereby the diaphragm may be connected to suitable actuating mechanism comprising an armature 4 and a drive rod 5. The base of the cone is provided with a flange 6 cut along 65 radial lines 7 to provide a series of tabs 8 extending around the entire flange and adapted to form a flexible support for the diaphragm. A plurality of parallel circumferential corrugations or embossed rings 9 70 are disposed on the surface of cone 1 and spaced apart suitable distances which may vary from $\frac{1}{4}$ inch to about $\frac{1}{2}$ inch from center to center. Each corrugation has a radius of about $\frac{1}{16}$ inch, and the number of 75 corrugations may vary, say from 5 to 10. With a 105° cone having a base of 7 inches in diameter, five embossed rings will greatly reduce rattling in the diaphragm. When a cone of this size is provided with ten rings, 80 however, the rattling is substantially completely eliminated.

The conical diaphragm shown on the drawing may be developed with an angle at the apex of 105° and a base having a diameter of approximately 9 inches. The cone may then be cut back to provide the tab 8, the cuts being spaced approximately $\frac{1}{4}$ inch apart to provide tabs approximately 85 $\frac{3}{4}$ inch long. The tabs when pressed outwardly reduce the diameter of the base to approximately 7 inches and provide thereby 90 a flexible supporting flange for the diaphragm.

What I claim as new and desire to secure 95 by Letters Patent of the United States is:

1. In a sound reproducing device, a fibrous, conical diaphragm having a series of spaced circumferential corrugations radially spaced from one another along the conical 100 surface of said diaphragm.

2. In a sound reproducing device, a conical, fibrous diaphragm, actuating mechanism therefor comprising an armature and a drive rod connecting the armature and cone, 105 said diaphragm being provided with embossed circumferential corrugations radially spaced from one another along the conical

surface of said diaphragm whereby parasitic vibrations in the cone are substantially eliminated.

3. In a sound reproducing device, a conical, paper diaphragm having a plurality of circumferential corrugations radially spaced from one another along its conical surface, each corrugation having a radius of sufficient magnitude to prevent any change in 10 the contour of the cone during its operation.

4. In a sound reproducing device, a conical, paper diaphragm having a plurality of spaced circumferential corrugations on the surface thereof, said corrugations being 15 spaced apart from $\frac{1}{4}$ to $\frac{1}{2}$ inch and having a radius of approximately $\frac{1}{4}$ of an inch.

5. In combination, a sound reproducing

device comprising a conical paper diaphragm having a diameter at its base of approximately 7 inches, and a plurality of 20 circumferential corrugations on the surface of the conical diaphragm said corrugations being spaced from $\frac{1}{4}$ inch to $\frac{1}{2}$ inch apart.

6. In combination, a sound reproducing device comprising a conical paper diaphragm having an angle at its apex of approximately 105° and a diameter at its base of approximately 7 inches, a plurality of 25 embossed rings on said diaphragm, said rings being spaced from $\frac{1}{4}$ inch to $\frac{1}{2}$ inch apart.

In witness whereof, I have hereunto set my hand this 28th day of January 1927.

ARTHUR G. ZIMMERMAN.
